LOUIS A. CASGRAIN, OF BEVERLY, MASSACHUSETTS, ASSIGNOR TO UNITED SHOE MACHINERY COMPANY, OF PATERSON, NEW JERSEY, A CORPORATION OF NEW JERSEY.

MACHINE FOR INSERTING FASTENINGS.

1,115,503.

Specification of Letters Patent.

Patented Nov. 3, 1914.

Application filed November 22, 1910. Serial No. 593,667.

To all whom it may concern:

Be it known that I, LOUIS A. CASGRAIN, a citizen of the United States, residing at Beverly, in the county of Essex and State of Massachusetts, have invented certain Improvements in Machines for Inserting Fastenings, of which the following description, in connection with the accompanying drawings, is a specification, like reference characters on the drawings indicating like parts in the several figures.

This invention relates to machines for inserting fastenings, particularly to machines for inserting screw-threaded fastenings, and is herein shown as embodied in a screw inserting machine of well-known type which is employed extensively for inserting screw-threaded wire into the soles of boots and shoes. It will be understood, however, that in its broader aspects the invention is not merely an improvement in machines of this type.

In its present commercial form the illustrated type of machine for inserting screw-threaded wire comprises a vertical wire carrying spindle, arranged to rotate normally at comparatively high speed, and two horizontal lateral shafts driven from said spindle, at comparatively low speed, by means of connections with the spindle comprising worm gears upon said shafts which engage a worm upon the spindle. One of the lateral shafts carries the cams through which the wire feeding, wire severing, work feeding and horn depressing mechanisms are operated.

In the machine as at present constructed the spindle and the lateral shafts are maintained continuously in operation, together with the cams and mechanisms hereinabove enumerated, with the exception of the wire feeding mechanism which is rendered inoperative to stop the insertion of fastenings by holding it out of operative relation to its continuously rotating cam. It has been found in practice that some disadvantages result from the present construction, in that the wire severing cutters become dulled by striking together when they are not operating to sever the wire, and that the various cams become worn by continuous use, a large part of which use takes place when the machine is not operating to insert fastenings.

The prior Patent No. 691,354, granted January 21, 1902, discloses a construction in which it has been attempted to overcome the disadvantages of the commercial construction by providing means for holding other mechanisms, besides the wire feeding mechanism, out of operative relation to their respective cams when the machine is not operating to insert fastenings. Although the mechanism shown in my prior patent above referred to accomplishes for the most part the objects which it was intended to accomplish, this mechanism is too complicated in its construction and not positive enough in its operation to be entirely satisfactory.

An object of the present invention is to provide a simple and compact construction which will not only accomplish all that was intended to be accomplished by the prior construction, but which can be easily applied to machines in commercial use, and which will contribute both to the life of the machine and to the ease of operation of the machine by the operator. To this end the invention contemplates the provision of means for throwing out of operation, at the time the insertion of fastenings is stopped, all of the parts of the machine which do not need to acquire considerable speed and momentum before they become operative, thereby preventing unnecessary wear of these parts, said means being, moreover, so constructed that it stops said parts in such relation to each other that when the insertion of fastenings is resumed they will perform their complete functions for the first fastening inserting operation.

One of the difficulties encountered in operating the commercial form of machine for inserting screw-threaded wire is that of controlling the length of the initial fastening. Since the only part of the machine which is thrown out of operation when the insertion of fastenings is stopped is the wire feeding mechanism, which is simply held out of operative relation to its cam, difficulty is encountered in so timing the parts which restore the wire feeding mechanism to the control of its cam that the length of wire fed into position to form the first fastening will be that required by the thickness of the work gaged. This results from the fact that the portion of the cam which effects the

movement of the wire feeding mechanism in the wire feeding direction may have partly passed its point of operation upon the wire feeding mechanism when the wire feeding mechanism is brought into operative relation to its cam. If the thickness of the work gaged, therefore, requires a length of wire greater than that which can be provided by the stroke imparted to the wire feeding mechanism by the part of the cam which has not passed the point of operation at the time the wire feeding mechanism is brought into operative relation to its cam, the first fastening inserted will be too short.

15 An important object of the invention is to obviate this difficulty and to this end the various mechanisms, as above suggested, are stopped in a predetermined operative relation to each other and also in such position 20 with respect to the functions which they are to perform that when the insertion of fastenings is resumed a full length stroke may be imparted to the wire feeding mechanism, if required, in feeding the wire into position 25 to form the first fastening to be inserted.

Other objects and features of the invention will become apparent when the following description and claims are considered in connection with the accompanying drawings, in which,—

Figure 1 is a side elevation of a machine for inserting screw-threaded wire, having embodied therein the present invention; Fig. 2 is a perspective detail of the clutches by which the lateral shafts are connected to and disconnected from the normally rotating spindle; Fig. 3 is a longitudinal section through one of the clutches; Fig. 4 is an exploded view of one of the clutches, parts being shown in section; Fig. 5 is a perspective view of the means for raising the horn into work supporting position as the machine is started; Fig. 6 is a detail view showing the means for stopping the cam shaft in the event that its momentum tends to keep it rotating when it has been disconnected from the spindle; Fig. 7 is a detail section showing an improved wire check, and Fig. 8 is a detail perspective of the wire check.

50 The machine to which the invention is shown as applied is of a well-known type, the illustrated machine being known to the trade as the rapid standard screw machine. This machine, in substantially its present 55 commercial form, is disclosed in United States Letters Patent 490,622, granted Jan. 24, 1893, to Louis Goddu and to this patent reference may be had for a more detailed description of parts herein illustrated but 60 not fully described.

The machine is constructed to insert screw-threaded wire into stock supported upon a horn 2, the wire being carried by a reel 4 mounted in a normally rotating spindle 6 arranged to turn about a vertical axis

and driven by a belt 8 upon a pulley 10 upon the upper end of said spindle 6, the belt 8 passing over idlers 12 to a driving pulley 14 mounted in the base of the machine and arranged to be clutched to a driven pulley 16 70 by any suitable clutch mechanism which may be operated through a wedge 18 connected to a treadle 20 in the machine base.

The spindle 6 is provided with a worm 22 which engages worm gears 24 and 26 upon lateral shafts 28 and 30 respectively, the shaft 28 being commonly known as the cam shaft, since the various cams by which the feeding and severing of the wire and the feeding of the work are effected and by 80 which the movement of the work support is controlled are mounted upon this shaft. The shaft 30 is provided to effect a more positive and a more even driving of the shaft 28 and to equalize the pressure upon opposite sides of the spindle 6, the shaft 30 being geared to the shaft 28 at its rear end, as more fully disclosed in the prior patent above referred to. A cam 32 formed upon one face of a cam disk 34 upon the shaft 28 90 controls the feeding of the wire. The feeding of the work is controlled from a cam groove 36 formed in the other face of the cam disk 34. The depression of the horn to permit the work to be fed is controlled from a cam 95 groove 38 in a second cam disk 40 upon the shaft 28, and the operation of the cutters by which the wire is severed after the end of the wire is screwed into the work is controlled by teeth or tappets 42 upon the cam disk 40, the construction and mode of operation of all of these parts being also more fully illustrated and described in said prior patent.

When the machine is being used to insert fastenings the spindle 6 is rotated continuously, the machine frame being provided with means for locking the treadle 20 in its clutch actuating position. In the machine shown in the Patent 490,622 above referred to, the lateral shafts 28 and 30 are also rotated continuously and the insertion of fastenings is interrupted by stopping the feeding of the wire. It has been found in practice, however, that when the parts are thus 115 kept in motion they are subjected to excessive wear, and, moreover, when the wire feeding mechanism is actuated to cause the insertion of fastenings to be resumed, the parts which have been held out of operation 120 will usually not come into operative relation to the parts which have been continuously operated at the proper time to provide an initial fastening of the length required by the thickness of the work gaged between the 125 horn and the foot plate or other work abutment.

An important object of the invention is to insure a proper timing of the various mechanisms when the insertion of fastenings is 130

started whereby the initial fastening inserted will be of the length required for the thickness of stock gaged. To this end all of the parts of the machine which are operated at comparatively low speeds are preferably thrown out of operation when the insertion of fastenings is stopped, and are stopped in such predetermined relations to each other that when they are again rendered operative the feeding mechanism may have imparted thereto a full length stroke, if required, for the first fastening inserted, and the other mechanisms shall operate in proper time relation to the feeding mechanism. A very convenient means for thus throwing out of operation the mechanisms above referred to is illustrated in the accompanying drawings and comprises twin clutches which may be actuated simultaneously to connect the lateral shafts 28 and 30 to the spindle 6 or to disconnect said shafts from said spindle. These clutches are so constructed and arranged that the shafts 28 and 30 will be disconnected from the spindle 6 at predetermined angles of their rotation, there being, in the illustrated construction, two of these disconnecting positions since the cams upon the shaft 28 are so constructed that they operate twice for each rotation of the shaft 28. The clutches are preferably so arranged that they serve to clutch the worm gears 24 and 26 to the shafts 28 and 30 respectively and to unclutch said gears from said shafts, whereby the gears 24 and 26 are rotated continuously from the worm 22 upon the spindle 6. The construction of these clutches is shown especially in Figs. 3 and 4 of the drawings, the clutches being identical in construction except that they are arranged to operate upon shafts turning in opposite directions. Each clutch comprises a toothed collar 44 clamped upon the hub 46 of one of the worm gears 24, 26, by a screw 48, the worm gear being free to turn upon its shaft until the clutch member 44 is engaged by another clutch member 50 having teeth 52 which interlock with the teeth 54 of the clutch member 44, the clutch member 50 being also provided with inwardly projecting teeth 56 which interlock with correspondingly shaped teeth 58 upon the lateral shaft, the teeth 58 extending longitudinally of the shaft for some distance to serve as guides for the clutch member 50 as said clutch member is moved into and out of clutching relation to the clutch member 44. Between the toothed enlargement of the lateral shaft and the end of the hub 46 of the worm gear is a washer 60.

The movement of the clutch member 50 longitudinally of the shaft into clutching engagement with the clutch member 44 is preferably effected automatically, the illustrated means for effecting such movement comprising a clutch casing 62 arranged to

turn upon a shouldered portion 64 of the lateral shaft 28 or 30 under the action of a spiral spring 66, said spring 66 having an offset end 68 which enters a notch 70 in the casing 62 and another offset end 72 which enters a notch 74 in the hub of a disk 76 clamped between the shoulder 64 of the lateral shaft and a nut 78 threaded upon the end of said shaft. The clutch member 50 is provided with spirally arranged grooves 80 into which project studs 82 formed upon the ends of screws 84 threaded into the casing 62. As the casing 62 turns relatively to the toothed enlargement of the lateral shaft, the studs 82 traveling in the slots 80 move the clutch member 50 longitudinally of said shaft.

In order to effect the movement of the clutch member 50 out of clutching relation to the clutch member 44, the clutch casing 62 is held against rotation while the lateral shaft 28 or 30 continues to rotate. The studs 82 being stationary, the spiral grooves 80 turn relatively to these studs and thus move the clutch member 50 longitudinally of the lateral shaft out of engagement with the clutch member 44.

The operation of the clutches is controlled by means connected with a treadle 86 fulcrumed at 88 in the machine base, the illustrated means comprising a lever 90 fulcrumed at 92 in the machine head and connected by a rod 94 with the rear end of the treadle 86, the rod 94 being yieldingly held in its lowermost position by a spring 96 connected at one end to a bracket 98 upon the machine frame and at its other end to a bracket 100 clamped upon the rod 94. At its forward end the lever 90 is provided with stop portions 102 which lie in the paths of rotation of lugs 104 formed upon the casings 62 of the twin clutches when the lever 90 is in its normal position, that is when the forward end of the lever 90 is in its uppermost position in which it is normally maintained by the spring 96.

Each of the clutch casings is provided with two of the lugs 104, since the worm gears 24 and 26 may be unclutched from the lateral shafts 28 and 30 at either of two angles of rotation of said shafts, in view of the fact that the cams upon the shaft 28 are shaped to operate for each half rotation of the shaft 28. When the treadle 86 is depressed, the forward end of the lever 90 is lowered and the stops 102 are moved out of engagement with the lugs 104 upon the clutch casings 62, thus permitting these casings to be turned under the action of the springs 66 to move the clutch members 50 longitudinally of the lateral shafts 28 and 30 into clutching relation to the clutch members 44, thereby simultaneously connecting the gears 24 and 26 to the shafts 28 and 30, respectively.

When the machine is operating to insert fastenings, the horn 2 is maintained normally in work clamping position by a comparatively strong spring 106 and is depressed 5 against the tension of said spring between the successive fastening inserting operations, to permit the feeding of the work, by means comprising a lever 108 carrying a cam roll 110 which enters a cam groove 38 in the cam 10 disk 40, and a pawl carrying slide 112 carrying a pawl 114 which engages a ratchet upon another slide 116, the slide 112 being connected by a link 118 to the lever 108 and the slide 116 being connected by a rod 120 and 15 toggle 122 and 124 to a lever 126 fulcrumed at 128 in the machine base. The lever 126 is connected at its forward end, by a rod 130, to the horn supporting shaft 132. The spring 106 surrounds the rod 120 and is confined 20 between the machine frame and a collar 134 threaded upon said rod. The work thickness compensating mechanism, comprising the slides 112 and 116, is of well-known construction and is more fully shown and described in the prior patent to Louis Geddu, 383,455 granted May 29, 1888.

In order to permit a final depression of the horn greater than that provided for the feeding of the work, the toggle 122, 124 has 30 been provided in the connections between the spring 106 and the horn 2, and means has been provided for straightening the toggle as the machine is rendered operative to insert fastenings and for causing the toggle to be broken as the machine is rendered inoperative. The illustrated means comprises a link 136 pivotally connected at one end to an extension of the toggle link 124 below its pivotal connection 138 with the 35 lever 126, said pivotal connection 138 being guided in a slot 140 in a toggle supporting casing 142 upon the rod 120. The link 136 is connected at its other end to an arm 143 upon the treadle 86, said link being provided 40 at its end with a slot 144 which provides lost motion when the treadle 86 is released to render the machine inoperative, so that the horn 2 is not lowered until the insertion or fastenings is stopped.

To insure the breaking of the toggle a 50 spring 146 is provided, one end of the spring being connected to the casing 142 and the other end pressing upon the toggle near its knee joint. A pin 148 extending through 55 the casing 142 from one side to the other provides a stop for determining the straightened position of the toggle.

The operation of the machine may be 60 briefly described as follows: The parts being in the position shown in Fig. 1, the operator places a shoe, or other work, upon the horn 2 and then depresses the treadle 86. As the treadle 86 is depressed, the link 136 is moved toward the rear, thus straightening

the toggle 122, 124 and raising the horn 2 65 into work clamping position, the spring 106 being placed under tension at the same time. The depression of the treadle 86 also rocks the lever 90 in a clockwise direction about its pivot 92 (Fig. 1) and moves the stops 70 102 out of engagement with the lugs 104 upon the clutch casings, 62, thereby permitting the gears 24 and 26 to be clutched to the lateral shafts 28 and 30. The spindle 6 being continuously in motion, the clutching 75 of the gears 24 and 26 to the lateral shafts 28 and 30 imparts motion to these shafts and to the cams upon the cam shaft 28, thereby rendering operative the wire feeding, wire severing, work feeding and horn depressing 80 mechanisms. So long as the treadle 86 remains depressed, the machine will insert a fastening for each half rotation of the shaft 28. When the treadle 86 is released, the lever 90 will move in a counter-clockwise 85 direction about its pivot 92, thus bringing its stops 102 into the path of movement of the lugs 104 upon the clutch casings 62, whereby the gears 24 and 26 are simultaneously unclutched from the lateral shafts 28 90 and 30 and the rotation of these shafts is stopped. The release of the treadle 86 permits the breaking of the toggle 122, 124 which is aided by the action of the spring 146 and also by the final movement of the 95 arm 143 of the treadle 86 when the pivot upon the arm 143 engages the end of the slot 144 in the link 136. The breaking of the toggle permits the descent of the horn 2 into such position that the work can be 100 easily replaced preparatory to the next fastening inserting operation.

The lateral shafts 28 and 30 are preferably disconnected from the spindle 6 at such times that they will stop just as the wire feeding and wire severing cams upon the shaft 28 have passed their operative positions and while the horn is depressed to permit the work to be fed. To prevent the momentum acquired by the cams from carrying them 110 too far beyond the desired stopping position, a check is provided, the illustrated check comprising a yoke 150 pivoted upon the cutter actuating slide 152, this yoke being 115 pressed by a spring 154 normally into the path of the cutter actuating tappet 42 upon the cam disk 38, whereby it engages said tappet and checks the rotation of the shaft 28 after it has been disconnected from the spindle 6 in the event that the momentum 120 of the cams carries them beyond the preferred stopping position, which is approximately that illustrated in Fig. 6. The yoke 150 also checks the tendency of the shaft 28 to turn under the action of the clutch 125 spring 66.

A wire check or wire brake is shown in Figs. 7 and 8 of the drawings and comprises

grooved wire engaging wheels 156 and 158 mounted in a casing 160 in the upper end of the spindle 6 and just below the reel 4, the casing having a wire receiving opening 162 through which the wire passes from the reel. The wheels 156 and 158 engage the wire upon opposite sides and are provided with pivots 164 and 166, respectively, which are supported upon springs 168, 170, the springs 10 168 and 170 pressing the pivots 164, 166 toward the upper end of converging openings 172 in the sides of the casing 160 whereby the wheels are pressed toward each other and grip the wire tightly between them, this 15 gripping action increasing if the wire is drawn up through the opening 162. When the wire is pulled down through the opening 162 and past the wheels 156 and 158, the springs 168, 170 permit the wheels to be 20 moved downward and this downward movement of the wheels brings the pivots 164 and 166 into the wider parts of the openings 172 in the casing 160, thereby permitting the wheels to separate to allow the wire to be 25 drawn freely past them. It will be noted that this wire check or brake is very simple in construction, as well as efficient in operation.

If it is desired to lower the horn 2 beyond the position into which it has been brought by the breaking of the toggle, this may be done by means of a third treadle 180 having an arm 182 which engages the underside of the lever 126 upon the side of the fulcrum 35 128 remote from that upon which the horn 2 is located.

The novel clutch herein shown, being a separate invention, has been made the subject-matter of a divisional application Serial No. 762,349, filed April 19, 1913.

Having described my invention, what I claim as new and desire to secure by Letters Patent of the United States is:—

1. A machine of the class described, comprising a continuously rotating wire carrying spindle, lateral shafts driven from opposite sides of said spindle, wire feeding means constantly connected to said shafts, and means for simultaneously disconnecting said shafts from said spindle while said spindle continues in operation.

2. A machine of the class described, comprising a continuously rotating wire carrying spindle, lateral shafts intergeared with each other and independently connected with said spindle, wire feeding means constantly connected to said shafts, and means for simultaneously disconnecting said shafts from said spindle while said spindle continues in operation.

3. A machine of the class described, comprising a continuously rotating wire carrying spindle, shafts connected to opposite sides of said spindle and driven therefrom, said

shafts being intergeared with each other, 65 wire feeding means constantly connected to said shafts, twin clutches through which said shafts may be connected to and disconnected from said spindle, and means for simultaneously operating said clutches. 70

4. A machine of the class described, comprising a continuously rotating vertical wire carrying spindle, horizontal shafts intergeared with each other and having independent worm and gear connections with 75 said spindle, wire feeding means constantly connected to said shafts, and means for simultaneously unclutching said shafts from said worm and gear connections while said spindle continues to rotate. 80

5. A machine for inserting screw-threaded fastenings, comprising in combination, a continuously rotating vertical wire carrying spindle, horizontal shafts intergeared with each other and having independent operative connections with said spindle, wire feeding and wire severing mechanisms normally connected with said horizontal shafts, and means for simultaneously disconnecting said shafts from said spindle to stop the 90 feeding and severing of fastenings while said spindle continues to rotate.

6. A machine for inserting fastenings, comprising in combination, a continuously rotating vertical wire carrying spindle, horizontal shafts intergeared with each other and having independent worm and gear connections with said spindle, wire feeding and wire severing mechanisms, a clutch between each of said lateral shafts and its worm 95 gear, and means for simultaneously operating said clutches whereby said shafts may be disconnected from said spindle while said spindle and said worm gears continue to rotate. 100

7. In a machine of the class described, wire feeding mechanism, wire severing mechanism, parallel shafts from which said mechanisms are operated, a single driving means arranged to turn said shafts in opposite directions, a clutch upon each of said shafts by which it may be connected to and disconnected from said driving means, each of said clutches comprising clutch controlling means arranged to turn with the shaft, 115 and a single means located between the shafts and arranged to be brought into the path of movement of both of said clutch controlling means whereby the connection of said shafts to the driving means and the disconnection therefrom may be effected simultaneously. 120

8. A machine of the class described, comprising a continuously rotating wire carrying spindle, lateral shafts driven from opposite sides of said spindle, wire feeding mechanism, wire cutting mechanism, means for simultaneously disconnecting said shafts 125

from said spindle while said spindle continues in operation and when said shafts are in predetermined angular position, and means for checking farther movement of said shafts.

In testimony whereof I have signed my

name to this specification in the presence of two subscribing witnesses.
